DESIGN FOR A CHRISTMAS TREE ORNAMENT

Charles Henry Hyman, Bronx, N. Y.

Application March 29, 1940, Serial No. 91,349

Term of patent 3½ years

To all whom it may concern:

Be it known that I, Charles Henry Hyman, a citizen of the United States, residing at 1985 Davidson Avenue, Bronx, in the county of Bronx and State of New York, have invented a new, original, and ornamental Design for a Christmas Tree Ornament, of which the following is a specification, reference being had to the accompanying drawing, forming part thereof.

I claim:

The ornamental design for a Christmas tree ornament, as shown.

CHARLES HENRY HYMAN.
